UNITED STATES PATENT OFFICE.

MAX BUCHNER, OF MANNHEIM, GERMANY.

REDUCTION OF AZO COMPOUNDS.

SPECIFICATION forming part of Letters Patent No. 700,671, dated May 20, 1902.

Application filed September 24, 1900. Serial No. 30,966. (No specimens.)

To all whom it may concern:

Be it known that I, MAX BUCHNER, a citizen of the Empire of Germany, residing at Mannheim, in the Empire of Germany, have invented 5 certain new and useful Improvements in the Reduction of Azo Compounds; and I do hereby declare the following to be a full, clear, and exact description of the invention, such as will enable others skilled in the art to which 10 it appertains to make and use the same.

This invention relates to the reduction of azo compounds; and the purpose of the same is to utilize the electric current for this purpose.

15 In my application for Letters Patent of the United States filed November 18, 1899, Serial No. 737,494, I have described and claimed a process of reducing nitro compounds to the corresponding amines by means of electrolytic action used in connection with a tin cathode or of an indifferent cathode and an electrolytic fluid containing tin, the process consisting, more specifically, in introducing the nitro bodies dissolved or suspended in 20 hydrochloric acid into the cathode-space of an electrolytic cell and submitting the same to action of the current. I have found in the course of subsequent experiments that this treatment may be applied also for the purpose 25 of reducing azo compounds. In this case, however, it is desirable to first coat the tin or indifferent cathode with a layer of tin sponge to maintain an elevated temperature, preferably about 60° centigrade, in the cathode-space and to operate with lower current densities than indicated in the aforesaid application.

30 It is to be observed that the preparation of the cathode may be dispensed with if at the beginning of electrolysis a relatively small quantity of electrolytically-precipitated powdered tin is added to the electrolytic fluid.

35 My invention therefore, broadly considered, consists in passing an electrolytic current through an azo body dissolved or suspended in an electrolytic fluid in the presence of tin, and more specifically in the use in connection therewith of an addition of tin to the tin or indifferent cathode and of an elevated 40 temperature.

45 My invention, moreover, comprises such

further features as will be hereinafter described and pointed out in the claims.

To enable those skilled in the art to carry out my invention, I will now describe the same 55 in detail by reciting the following examples, which constitute what I consider the preferable embodiment of the same.

Example 1—Reduction of para-amido-azo-benzol to paraphenylenediamine.—An electrolytic cell is divided into an anode and a cathode space by a suitable diaphragm, as will be readily understood. A ten-per-cent. solution of sulfuric acid is poured into the anode-space, and anode of indifferent anode material, 60 such as lead, is introduced. Into the cathode-compartment I pour a mixture consisting of 48.7 parts, by weight, of chlorid of para-amido-azo-benzol, five grams of powdered electrolytically-precipitated tin dissolved or suspended in one hundred parts, by volume, of water and two hundred and fifty parts, by volume, of fuming hydrochloric acid. An electric current is then passed through a tin or indifferent cathode. The liquid mixture is 65 vigorously agitated or stirred during the course of the electrolysis, whose completion is indicated by the commencement of an active evolution of hydrogen. The current employed is preferably of a density of three 70 hundred to four hundred amperes per square meter, and the temperature employed in the cathode-space is advantageously 60° centigrade. The resulting paraphenylenediamine is precipitated in the form of a chlorid by 75 saturating the cathode electrolyte with hydrochloric-acid gas in the cold, the anilin, which is produced at the same time, remaining in solution.

Example 2—Reduction of orange II to 90 amido-beta-naphthol.—The same arrangement of electrolytic cell and the same materials for the anode-space as in Example 1 are employed in this case. I charge the cathode compartment with a mixture of thirty- 95 three parts, by weight, of orange II, two hundred and fifty parts, by weight, of water and two hundred and fifty parts, by weight, of fuming hydrochloric acid. I also add a quantity of powdered tin, as in the first example, 100 if an indifferent cathode is employed, and, in general, conduct the operation as in said

example. Even if a tin cathode is employed the addition of tin is desirable, though not indispensable. The amido-beta-naphthol produced under these conditions is isolated and 5 purified according to well-known methods.

What I claim, and desire to secure by Letters Patent of the United States, is—

1. The process of reducing azo compounds which consists in passing an electric current 10 through such azo compounds dissolved or suspended in an electrolytic fluid capable of dissolving tin in the presence of tin, the azo compound and tin being arranged in the cathode-compartment.

15 2. The process of reducing azo compounds which consists in passing an electric current through such azo compounds dissolved or suspended in an electrolytic fluid containing tin, the azo compound and tin being arranged 20 in the cathode-compartment.

25 3. The process of reducing azo compounds which consists in passing an electric current through such azo compounds dissolved or suspended in an electrolytic fluid capable of dissolving tin in the presence of tin and at an elevated temperature, the electrolytic fluid being capable of dissolving tin and the tin

and azo compound being arranged in the cathode-compartment.

4. The process of reducing azo compounds 30 which consists in passing an electric current through such azo compounds dissolved or suspended in an electrolytic fluid capable of dissolving tin containing tin and at an elevated temperature, the azo compound and tin 35 being arranged in the cathode-compartment.

5. The process of reducing azo compounds which consists in charging the cathode-space of an electrolytic cell with a mixture of the azo compound with hydrochloric acid and 40 water and passing the electric current therethrough in the presence of tin.

6. The process of reducing azo compounds which consists in charging the cathode-space of an electrolytic cell with a mixture of the 45 azo compound and powdered tin with water and hydrochloric acid and then passing the electrolytic current through the mixture.

In testimony whereof I affix my signature in presence of two witnesses.

MAX BUCHNER.

Witnesses:
